UNITED STATES PATENT OFFICE.

FREDRICK F. PINNOW, OF BROADHEAD, WISCONSIN, ASSIGNOR OF ONE-HALF TO LEWIS W. TERRY, OF BROADHEAD, WISCONSIN.

LATCH FOR SWINGING AND SLIDING DOORS.

1,128,502.

Specification of Letters Patent. Patented Feb. 16, 1915.

Application filed July 13, 1914. Serial No. 850,638.

To all whom it may concern:

Be it known that I, FREDRICK F. PINNOW, a citizen of the United States, residing at Broadhead, in the county of Green and State 5 of Wisconsin, have invented certain new and useful Improvements in Latches for Swinging and Sliding Doors; and I do declare the following to be a full, clear, and exact description of the invention, such as 10 will enable others skilled in the art to which it appertains to make and use the same.

My invention relates broadly to the class of locks or latches and more particularly to the latter.

15 The object of the invention is to improve upon the construction of devices of this character to such an extent as to provide a simple and novel form of yoke for guiding a pivoted latch bar as to allow it to co- 20 act effectively with the yoke.

With this and minor objects in view, the invention resides in the specific construction and arrangement of parts herein described and claimed and shown in the drawings 25 wherein:

Figure 1 is a side elevation of a portion of a sliding door and its frame, showing the application of my invention thereto, the door being slightly open; Fig. 2 is a similar view with the door closed and locked in closed position; Fig. 3 is a vertical transverse section taken along the plane of the line 3—3 of Fig. 1; Fig. 4 is a detail side elevation partly in section, showing the form 35 of keeper employed and illustrating the manner in which the active end of the latch bar coacts with said keeper; Fig. 5 is a detail vertical section taken along the plane of the line 5—5 of Fig. 1; Fig. 6 is a vertical section taken on the line 6—6 of Fig. 40 3; Fig. 7 is a perspective view of the pivoted latch bar and the parts carried thereby; Fig. 8 is a similar view of the yoke employed in connection with the latch bar; Fig. 9 is a perspective view of the form 45 of keeper employed for securing the door in closed position; Fig. 10 is a face view of a door frame illustrating an edge view of a door hinged therein and showing the manner in which the device may be employed for locking the door in open position; and Fig. 11 is a horizontal section taken on the line 11—11 of Fig. 10.

50 In the embodiment illustrated, in the drawings, I have shown my invention as in-

cluding a pivoted latch bar 1, guide yoke 2 therefor, a keeper 3 for receiving the active end of the bar, and numerous details of construction to be herein described. The latch bar 1 is in the form of a flat rectilinear bar 60 having one of its ends provided with a transverse pivot opening 4 while its opposite end portion is notched upon its upper and lower edges as indicated at 5, the free end of said bar, adjacent said notches, being 65 beveled on its upper and lower edges as indicated at 6 whereby a pair of noses 7 are formed upon the upper and lower edges of said bar. The rear surface of the bar 1 is preferably rounded as most clearly seen in 70 Fig. 5, this provision being made at the end portion of the bar carrying the noses 7 and being designed for a purpose to be herein-after set forth. The intermediate portion of the bar 1 is here shown as being enlarged 75 at 8 and provided with an upright pin 9 rising from said enlarged portion, with a depending pin 10 depending from said portion and with a comparatively long pin or finger 11 projecting inwardly from said portion. Between the enlargement 8 and the notches 5, the outer side of the bar 1 is provided with a laterally extending lug 12 through which an opening 13 is formed for the reception of a pad lock in a manner to 80 appear while a rectangular head 14 is formed on the free outer end of said lug, the upper and lower ends of said head 14 rising and depending respectively from their juncture with said lug to form upper and 85 lower noses 15.

In applying the device to either a swinging or sliding door, a suitable pivot bolt or screw 16 is inserted through the opening 4 and into the sliding door D or hinged door 95 D' as the case may be, a suitable slot S being formed through the body of the door for the reception of the pin or finger 11 whereby the latch may be operated from the inside 100 of the door. When in this position, the notches 5 and noses 7 project beyond the free edge of the door as clearly set forth in the drawings and the upper and lower pins 9 and 10 are received respectively by 105 a groove 17 and a notch 18 which are respectively formed in an upper elliptical attaching plate 19 and in a lower substantially rectangular attaching plate 20, the outer sides of these plates 19 and 20 being integrally united with an upright body portion 110

21 of the yoke 2. It will be noted more particularly by reference to Figs. 3 and 6 of the drawings that the inner opposed edges of the plates 19 and 20 are spaced one from the other a distance considerably greater than the width of the latch bar 1, this provision being made in order that said bar may be allowed the proper amount of vertical movement. When the parts are assembled as above set forth, a coil spring 22 is located in the groove 17, said spring encircling the uppermost pin or stud 9 and bearing against the adjacent upper edge of the bar 1, whereby the latter is normally forced downward into contact with the upper edge of the plate 20.

From the above set forth construction, it will be seen that should it be necessary to employ the device in connection with a door opening toward the left instead of toward the right as indicated in the drawings, the bar 1 may be reversed, and may be completely turned over thereby allowing the device to be employed with a door opening in either direction with the same effect.

The keeper 3, most clearly seen in Fig. 9, comprises an upright rectangular block or plate 23 which is secured to the frame of the door adjacent the active end of the bar 1, the upper and lower corners of said block, adjacent the door, being provided with noses 24 having their outer edges rounded as clearly seen in the drawings, the noses being adapted to coact with the notches 5 and the noses 7 for retaining the sliding door D in closed position.

As a means for preventing the active nose 7 from moving outwardly out of engagement with the active nose 24, a pair of upright flanges 25 are provided which are formed integrally with the outer surface of the block 23 and which rise and depend from the noses 24 as clearly seen in Fig. 9. These flanges 25 also become active when the device is employed upon a swinging door as will be hereinafter set forth.

For the purpose of allowing the bar 1 to be locked against movement relative to the keeper 3, said keeper is preferably provided with a C-shaped loop 26 whose opposite ends 27 are brazed or otherwise secured to the edge of said block adjacent the door D, whereby a pad lock L (see more particularly Fig. 2) may be inserted through the loop 26 and through the opening 13.

Under ordinary circumstances, when closing the sliding door D, the lower bevel 6 will contact with the uppermost nose 24 thereby raising the active end of the bar 1 against the tension of its spring 22, which latter now acts to return said bar to normal position, in which position, the active nose 7 lies in rear of the active nose 24 thereby preventing the bar from being opened until the latch is raised. In some

cases however, the door D has become warped to such an extent as to prevent the bevel from properly contacting with the nose 24 thereby preventing the latch from operating properly and in cases of this kind, it is simply necessary to force the door inwardly, thus causing the rounded portion of the bar to contact with the rounded surface of the active flange 25 whereby the bar will be raised against the tension of its spring which now acts to position the parts as clearly seen in Fig. 6. It will therefore be seen that although the bevels 6 are primarily designed to coact with the noses 7 for raising the latch bar, that the rounded surface of the bar 1 operates to equal advantage when contacting with the rounded surfaces of either of the flanges 25, for producing the same end. It may here be explained that the keeper 3 is constructed in the double formation, illustrated in the drawings in order that it may be reversed to coöperate with the bar 1 when the latter is employed in connection with a door opening in either direction.

In Figs. 10 and 11 the swinging or hinged door D' is equipped with a latch bar 1 formed and mounted in identically the same manner as the bar previously described, the frame of said door is provided with the keeper 3 identical with the form previously described, and a supplemental keeper 3' is shown as being carried by an upright post P which constitutes a stop for limiting the outward movement of the door, the keeper 3' having a nose similar to the flanges 25 which coacts with the upper or lower nose 15 on the lug 12 as the case may be, thereby effectively retaining the door in open position. It will be understood that when the device is employed in this connection, the rounded end of the bar 1 constitutes the means for raising said bar against the tension of its spring and that the flanges 25 and noses 7 constitute means for preventing opening of the door.

From the foregoing description, taken in connection with the accompanying drawings, it will be seen that I have provided an extremely simple device for carrying out the objects of the invention yet one which may be employed in connection with either sliding or swinging doors and with doors opening either toward the right or toward the left. It will also be clearly seen that although the flanges 25 are designed primarily for use when the device is employed for locking a swinging door, said flanges also perform useful functions when the device is employed for retaining a sliding door in closed position.

Having thus described my invention, what I claim as new and desire to secure by Letters Patent is:

1. In a device of the character described,

a yoke member for attachment to a door, said member comprising an upright body portion, an attaching plate formed on the rear side of one end thereof, said plate being provided in its rear face, with an upright groove terminating a distance from its outer edge and opening through its inner edge, a second attaching plate formed on the rear side of said body portion at its opposite end, said plates being spaced one from the other and the second mentioned plate being formed with a notch in its inner edge and alined with said groove, a latch bar adapted to be pivoted at one end to a door, the intermediate portion of said bar being slidably mounted between said plates and contacting with said body portion, a stud on the one edge of said bar and projecting into said notch, a stud on the other edge of said bar and alined with said groove, and a coil

spring encircling said last mentioned stud and located in said groove.

2. A device of the character described including an elongated rectilinear latch bolt having a transverse opening in one end for 25 the reception of a pivot pin, its opposite end portion being shaped to engage a keeper, pins formed on the upper and lower edges of the bar at its intermediate portion, a yoke receiving said intermediate portion and having grooves receiving said pins therein, and a coil spring encircling one of said pins and located in one of said grooves. 30

In testimony whereof I have hereunto set my hand in presence of two subscribing witnesses. 35
